UNITED STATES PATENT OFFICE.

JOSEPH H. KINCAID, OF EVANSTON, ILLINOIS, ASSIGNOR TO CENTRAL SCIENTIFIC COMPANY, OF CHICAGO, ILLINOIS, A CORPORATION OF ILLINOIS.

PNEUMATIC TROUGH.

Application filed August 21, 1928. Serial No. 130,723.

This invention relates to pneumatic troughs for laboratories for schools, colleges, experimental departments of factories, and the like.

The principal object of the invention is the provision of a new and improved pneumatic trough so constructed that it will be held spaced from its support and at the same time will be so fabricated that any desired number may be nested for shipment without danger of injuring the devices or any portion thereof.

Another object of the invention is the provision of a new and improved pneumatic trough that is simple and rugged in construction, cheap to manufacture, easily assembled, efficient in use, and one that is not likely to become damaged or injured during shipment in quantities.

Other and further objects and advantages 20 of the invention will appear from the following description taken in connection with the accompanying drawings, in which

Fig. 1 is a perspective view of the pneumatic trough;

Fig. 2 is a vertical section thereof;

Fig. 3 is an end view of a plurality of nested pneumatic troughs; and

Fig. 4 is a top plan view thereof.

In the construction of pneumatic troughs 30 which are used for the collection of gases over water it is desirable that they be provided with means for supporting them in spaced relation above the table or desk or other supporting surface, because in certain experiments the water contained in the trough is hot and consequently the hot container would injure the finish on the desk or table if permitted to come in direct contact therewith. It is necessary also to provide an overflow 40 pipe for removing the excess water from the trough. Each trough is also supplied with a test tube or gas container support.

Heretofore, great difficulty has been experienced in shipping devices of this character 45 because of their peculiar construction, and consequently each device is usually packed separately. A separate package for each device is not only expensive but requires a great deal of additional labor in preparing each 50 article for shipment.

The present invention contemplates a construction in which each device will be provided with the necessary parts and the whole be so constructed that any desired number 55 may be nested and prepared for shipment in

a single, comparatively small package, thereby eliminating the necessity for a single package for each article.

In the form of the device selected to illustrate one embodiment of the invention, the pneumatic trough is designated generally by the reference character 9. The trough may be made from any suitable material, and is adapted to contain water under which gas is adapted to be collected in a manner well known in the art. The device shown is made from sheet metal bent to form a receptacle 10 having its upper edge portion bent about a wire 11 to form a bead 12 for reinforcing the same.

The receptacle is preferably though not necessarily rectangular in horizontal section, and its end and side walls converge slightly toward the bottom of the receptacle.

A suitable overflow pipe 13 is provided in 75 one end of the receptacle in proximity to the bead 12.

Suitable legs 14 are provided for supporting the receptacle. These legs are attached to the bottom of the receptacle within the 80 confines of the periphery thereof. Each leg is curved or convex on its lower end whereby the same will not injure the finish of a surface on which the trough may be placed. The length of the legs 14 is substantially the same 85 as the distance between the lower portion of the overflow pipe 13 and the top of the receptacle 10 whereby when the receptacles are nested the legs will support the inner receptacles from the bottom walls of the outer 90 ones with the overflow pipes extending outwardly over the end walls of the corresponding outer receptacles and in close proximity thereto.

A suitable support 15 is provided for holding the test tube or other gas container in position for collecting the gas. This support is provided with a body portion 16 having one or more openings 17 for receiving the gas collecting container and the tube or conduit for conducting the gas from the generator to a point beneath the gas collecting container, as is usual in such constructions. Each end of the body portion 16 is provided with a hanger 18 having a hook-shaped upper 100 end 19 for engaging over the reinforcing bead 12 for supporting the body portion 16 below the top edge of said trough as clearly shown in Fig. 1. The hangers are inclined 105 at substantially the same angle as the walls 110

of the receptacle 10 whereby the supports will not only fit into said receptacle, but may be nested as clearly indicated on the drawing.

In preparing a shipment of troughs, the supports 15 are removed and a number of the troughs are nested to form a package of the required size, as shown in Figs. 2 and 3. The supports 15 are nested and placed in the upper trough as indicated in Figs. 2 and 4, after which the package thus assembled is ready to be placed in a suitable shipping crate or box.

I claim as my invention:

A pneumatic trough comprising a receptacle tapering downwardly and of a substantial depth, an overflow pipe secured in an

opening in one wall of said receptacle adjacent to the upper edge thereof, and extending outwardly a substantial distance for conducting excess fluid from said receptacle to a point out of contact with said wall, and supporting legs extending downwardly from the bottom wall of said receptacle and arranged within the contour thereof, said legs being of such length that when a plurality of said receptacles are nested for shipment said pipes each will be supported adjacent to but out of contact with the upper edge of the next adjacent outer receptacle.

In testimony whereof I affix my signature.

JOSEPH H. KINCAID.
